(57) **CLAIM**

The ornamental design for a graphical user interface for computer screen, as shown and described.

DESCRIPTION

A portion of the disclosure of this patent document contains material to which a claim for copyright and trademark is made. The copyright and trademark owner has no objection to the facsimile reproduction by anyone of the patent document or the patent disclosure, as it appears in the Patent and Trademark Office file or records, but reserves all other copyright and trademark rights whatsoever.

The sole FIGURE is a front view of our graphical user interface for computer screen showing our new design.

The broken line showing of a computer screen is included for the purpose of illustrating environmental structure and forms no part of the claimed design. The rectangles shown in dot-dash broken lines are unclaimed boundary lines, and the area within, forms no part of the claimed design.
